APPARATUS FOR TESTING MATERIALS
BY FLEXURE

Sam Tour, New York, N. Y., and Charles H. Marshall, Short Hills, N. J., assignors to Lucius Pitkin, Inc., New York, N. Y., a corporation of New York

Application January 22, 1934, Serial No. 707,710

5 Claims. (Cl. 265—17)

This invention relates to the determination of the physical characteristics and more particularly the bending characteristics of various fabricated shapes such as wires, rods and strips, 5 sheets, tubes, bars and the like, whether metallic or non-metallic or whether of elastic or non-resilient material; and has for its particular objects the expeditious testing, with precision, of such materials and the provision, for this purpose of a simple, inexpensive and rugged apparatus. Our invention is fully set forth in the following detailed description with drawing forming a part thereof, in which latter is illustrated an apparatus embodying our invention and 10 adapted for carrying out our improved testing method. Referring to the drawing

Figure 1 is a front elevation of our improved testing apparatus;

Fig. 2 is a central transverse section upon the line 2—2 of Fig. 1;

Fig. 3 is a diagrammatic view of the electric "hook up"; and

Fig. 4 is a typical graph prepared from the data obtained from a selected specimen of material tested in our improved apparatus.

The reference numeral 1 designates a metallic shell which is mounted upon a suitable base 2, said shell having apertured front and rear faces 3 and 4 respectively. A metal shaft 5 is substantially centrally mounted in said casing, the same being supported in a bushing 6 which is positioned in the aperture a of the rear face. Such shaft is provided with a worm gear 7 which is splined thereto and meshes with a worm 8 carried on a shaft 8' that is suitably mounted in brackets 9 carried by said rear face 4. Said worm is adapted to be rotated by a hand crank 10 that is rigidly secured to the worm shaft 8'. The shaft 5 and said gear 7 are electrically insulated from the said bushing 6 by means of insulating sleeve b and insulating washers c that are formed of fiber, hard rubber or the like. A disc 12, having a hollow spindle 13 projecting inwardly therefrom, is mounted on said bushing 6 and preferably ball bearings 14 are interposed between said spindle and said bushing in order to reduce to a minimum the friction of rotation of said disc. Said disc is centrally apertured, as indicated by the reference letter d, to permit of the projection therethrough of said shaft 5 and an annular collar 15, carrying a pointer 16, is frictionally mounted on the inner end or cylindrical shoulder 17 of said shaft, which latter has a peripheral groove 18 thereon adapted 55 to receive the inner end of a set screw f that

serves to prevent longitudinal movement of the shaft 5. The shoulder 17 and said collar 15 are also insulated from said bushing 6 by an insulating washer e.

A clamp 19 is rigidly secured to the front end 5 of said shaft 5, the same having a clamping screw 19' for effecting the clamping of an article to be tested in the desired position in said clamp.

An arcuate scale 20 is marginally secured to the disc 12, the same being adapted to co-operate with the aforesaid pointer 16, and this scale is provided with an integral pointer 21 that is adapted, when the disc 12 rotates, to travel over a second adjustable percentage scale member 22 that is marginally secured to the face 3. Said 15 disc 12 is provided with a plurality of diametrically disposed apertures 25, which apertures are arranged in pairs, the corresponding apertures of each pair being the same radial distance from the center of the disc. These apertures are 20 adapted to receive metal pins of roller members 26, 26' which are identical in weight with each other and accordingly, adapted to counter-balance each other, so that when the pin of roller member 26 is inserted in one of the apertures on 25 one side of the disc and the pin of its counter part 26' is inserted in the corresponding aperture on the other side of the disc, the original center of gravity of said disc will remain unchanged. Said disc 12 is also provided with a 30 series of pins 27, 27' which are also disposed along the same radius and which pins or either of them, are adapted to receive one or more weights 28.

In order to enable the operative to more accurately determine the bending characteristics of metal specimens, we provide an indicator, such as an electric lamp 29 which is preferably mounted near the top of the face 3. The circuit of said lamp is controlled by the switch 30. 40 A battery B serves to supply current to the lamp filament and a shoe 31 electrically connects the clamp 19, via the shaft 5 and gear 7, with the said battery. As shown in Fig. 3, the electrical hook-up is such that when the switch is closed, 45 the lamp 29 will be illuminated the instant the free end of the specimen x contacts with the stop pin 26, since the current will flow from the positive terminal of the battery through the switch 30 to the lamp filament, thence via metal 50 face 4 to the metal disc 12, to the pin 26, the metal specimen x, the clamp 19, the shaft 5, the gear 7, the brush 31 and thence to the negative terminal of the battery.

The method of procedure in order to test the 55

bending characteristics, as well as to determine the elastic limits of a selected metal specimen in the above described apparatus is as follows:—

- 5 A test specimen, such as the metal wire *x*, which must be of a minimum length to at least extend beyond the center of the first aperture 25 at the right side of the disc 12, is rigidly clamped in the clamp 19 in the position shown 10 in Fig. 1. A weight 28, for example a 100 gram weight is then placed on the pin 27', the axis of said pin being a fixed or predetermined distance from the center of said disc, for example for convenience of calculation say 10 centimeters. 15 Also the scale 22 is so calibrated that on rotation of the disc 12 any point from zero to the end thereof will read in terms of percentage of gram centimeter capacity or of the total bending increment applied, such total being the 20 weight on pin 27' multiplied by the distance of the latter from center of disc 12. Since the specimen *x* is long enough to extend beyond the second aperture 25 to the right of the disc, which is located 10 centimeters from the axis 25 of the disc 12, the pin 26 is inserted in such second aperture and an identical pin 26' is then inserted in the second aperture from the center on the left side of the disc in order that such latter pin may, as previously explained, counter- 30 balance the weight of the first pin 26. By means of the crank 10, the disc is now rotated in an anti-clockwise direction until the lowermost edge of the pin 26 just engages the uppermost edge of said test specimen, but without exerting any 35 pressure and at that instant if the switch 30 has been turned to an "ON" position, the light 29 will be illuminated, due to the closing of the circuit through the filament thereof. The pointer 16, which as stated is mounted on the 40 friction collar 15, is now moved but without changing the position of the disc 12 until it indicates the zero position on the scale 20, and then the adjustable scale 22 is also adjusted so that the pointer 21, carried by the former 45 scale 20 indicates the zero position on the latter scale 22.

The test is then proceeded with by turning the crank 10 so as to produce a slight amount of bending of the test specimen *x* and then, as 50 the disc 12 is slowly rotated, readings are taken from scale 20 indicative of degrees of bending and readings are taken from scale 22 indicative of the load in gram-centimeters, such readings being continued until the desired amount of 55 bending of the specimen has been accomplished and/or the desired amount of load has been applied. Thereupon the load is released by slowly reversing the direction of rotation of the worm, by means of the hand crank 10, and by 60 taking a reading on the scale 20 at the moment the light is extinguished, thus indicating at zero load the amount of bending of the specimen or the amount of the permanent set of the test specimen thereby obtained. The readings ob- 65 tained from observing movements of the pointer 21 across the scale 22 serve to indicate the amount of rotation (anti-clockwise) of the disc 12 (and the consequent amount of displacement of attached weight 28), such rotation being pro- 70 duced by any pressure, however, slight, exerted by the test specimen against the pin 26 which rotation gradually elevates the weight from the zero position (shown in Fig. 1) to a higher position on the right side of the apparatus until 75 such time as the test specimen takes on a per-

manent set, whereupon in those cases where the specimen tested was inherently resilient, such for example as a steel wire, the speed of movement of the pointer 21 across the scale 22 will drop since the indicated load increment will then only correspond to the bending characteristics of the specimen unassisted by the original resiliency or elasticity thereof.

Before any pressure is applied to the pin 26 by the test specimen *x*, the weight 28 will, due 10 to gravity, assume the lowermost position shown in Fig. 1.

The data obtained from the aforesaid readings on the scale can, if desired be plotted in the form of a graph, such as illustrated in Fig. 4, where- 15 in the vertical readings can be translated into the load in gram-centimeters and the horizontal readings represent the amount of bending in degrees. As shown by the graph 2, which represents a test conducted on a selected specimen 20 such as *x*, the bending proceeds at a substantially uniform rate as the load is steadily increased until a load representing say about 600 gram-centimeters has been applied, after which point the bending increases at a more rapid 25 rate with a slower rate of increase in load, thus indicating that whatever resiliency was originally present in the specimen, has been substantially overcome.

The electric indicator, such as the lamp 29, 30 also serves to indicate whether the test specimen has been deformed after the application of a predetermined load or from a predetermined amount of bending, since if the lamp is ext- 35 putished before the pointer 16 is returned to 0, the reading on the scale 20 at the moment the light is extinguished will indicate the amount of permanent deformation which has occurred; whereas if the lamp remains illuminated upon the return of the pointer 16 to 0 it will mean that 40 the test specimen has not been affected by the predetermined amount of load or amount of bending to which it has been subjected.

The fact that the member 26 constitutes a roller which is capable of free rotation on the 45 pin on which it is mounted, eliminates any tendency for such roller to bind against or cling to the metal specimen during the bending of the latter, with the consequence that the readings on the respective scales are unaffected. The 50 counterbalancing roller member 26' and its pin are of identical weight with roller 26 and its associated pin but, if desired, a plain pin of such a weight identical with that of roller 26 and its pin 27 may be substituted for the roller 26' and 55 its pin.

The apparatus is useful for a variety of purposes, for example, in testing a specimen of wire, either spring wire or pliable wire, it is desirable that the specimen to be tested be clamped sub- 60 stantially as shown in Fig. 1 and preferably so that its longitudinal axis is substantially coincident with a horizontal diameter extending through the center of the disc 12, and likewise, that said specimen be so clamped that the right- 65 hand vertical edge of the platen or base plate of the clamp, as viewed in Fig. 1, passes through the axis of shaft 5. The specimen so tested should be, when clamped in the central supporting clamp, at least long enough to extend beyond a 70 pin inserted in one of the apertures 25. If the specimen is long enough to admit of the load- applying pin being inserted in the second aper- 75 ture to the right of the center of said disc 12, then said aperture is at a distance of 10 centi-

meters from the center of said disc and a 100 gram weight is placed on the pin 27' also located 10 centimeters from the center of the disc, then a reading of 20 on the scale 20 and a reading of

- 5 40 on the scale 22, will indicate that the specimen tested had been deflected 20° on the application of a load of 400 gram-centimeters, since the readings on the scale 20 are directly in degrees of bending and the readings on scale 22 are in 10 percentage of gram-centimeter load; in this case 40% of 1000 gram-centimeters. If, however, the pin 26 is located in the first aperture 25 and such aperture is 5 centimeters distant from the center of the disc then, with the same weight applied 15 to the pin 27', the actual load required to effect the aforesaid amount of 20° of deflection, would be 800 grams at 5 centimeters or again 400 gram-centimeters. Again, if the weight is applied to pin 27 and such pin is located 5 centimeters from 20 the center of the disc, then while the percentage reading indicated on the scale 22 will be the same as when the weight is placed on pin 27' and the same located 10 centimeters from the center of the disc, nevertheless the actual loading figured 25 in gram-centimeters will be one-half.

For measuring the stiffness of very thin or delicate materials, which bend of their own weight when held horizontal the disc 12 may be rotated until pin 27', without any weight applied thereto, is at a definite angular distance from its lowermost position shown in Fig. 1 and preferably the disc is clamped with a separate individual clamp (not shown) in that position. The clamp 19 is then rotated so that the material to be tested, which is clamped therein, substantially coincides with a vertical, rather than a horizontal axis. The pointer 16 is then set at zero on scale 20 and the specimen rotated by rotating clamp 19 until the specimen contacts with either pin 27 and pin 27' and then the difference between the 35 angular reading on scale 20 and the definite angle at which disc 12 was clamped will be the amount of bending of the specimen due to its own weight and will be a relative indication of the stiffness 40 of the material. A load may be applied to the lower end of the specimen tested if desired and usually this is preferable where the specimen is so light or flexible that normally it tends to curl when not under load.

- 45 50 For measuring the dynamic stiffness of materials the specimen may be clamped in clamp 19 so that the specimen hangs vertically and just touches the left side of pin 27, the pointer is then set at zero on scale 20, the desired weight 28 is put on pin 27', the disc 12 is rotated by hand to any desired load percentage as indicated on scale 22 and then the disc 12 is suddenly released and allowing the disc 12 to swing in a clockwise direction and allowing pin 27 to strike the specimen 55 thus bending it in a clockwise direction. With the disc 12 then at rest with weight 28 in its lowermost position the specimen is rotated in a counter-clockwise direction by rotating clamp 19 until the specimen again just touches the left 60 side of pin 27. The angular degree of bending of the specimen is then indicated by pointer 16 on scale 20 and this degree of bending is inversely proportional to the dynamic stiffness of the material being tested.

- 65 70 Various changes in the construction of the aforesaid apparatus and in the manner of operating the same from that specifically described herein may be made without departing from the spirit of our invention as embraced within the scope of the appended claims.

Having thus described our invention, what we claim and desire to obtain by United States Patent is:

1. In an apparatus for measuring the bending characteristics of material, the sub-combination comprising a rotatable support adapted to receive a specimen of material to be tested, a rotatable load-applying member mounted on said support and movable relative thereto and a pointer carried by said support and adapted to rotate there- 10 with but being capable of adjustment relative thereto, a co-operating scale carried by said load-applying member, a second pointer carried by said load-applying member and a co-operating adjustable scale mounted in proximity to but sepa- 15 rate from said load-applying member.

2. In an apparatus for measuring the bending characteristics of material, the sub-combination comprising a rotatable support adapted to receive a specimen of material to be tested, a rotatable 20 load-applying member mounted on said support and movable relative thereto and a pointer carried by said support and adapted to rotate there- with but being capable of adjustment relative thereto, a co-operating scale carried by said load- 25 applying member, a second pointer carried by said load-applying member, a co-operating adjustable scale mounted in proximity to but separate from said load-applying member and an electric signal adapted to indicate when contact 30 has been made or broken between a test specimen mounted in said support and said load-applying member.

3. In an apparatus for measuring the bending characteristics of material, the combination com- 35 prising a shaft mounting, a shaft journaled there- in, a pointer carried by said shaft which normally moves therewith but virtually engages the same so as to be capable of movement, when pressure is applied thereto, peripherally of said 40 shaft, but is incapable of movement longitudinally of said shaft, means for applying a pre- determined load to said specimen of material to be tested while effecting rotation thereof, in- cluding a disc member through which said shaft 45 projects, such disc being capable of relative movement with respect to said shaft, said disc carrying a scale over which said pointer is adapt- ed to travel during the relative movements of said shaft and disc, means for mounting on said 50 shaft a specimen to be tested and means for rotating said shaft.

4. In an apparatus for measuring the bending characteristics of material, the combination com- 55 prising a shaft mounting, a shaft journaled there- in, a pointer carried by said shaft which normally moves therewith but virtually engages the same so as to be capable of movement, when pressure is applied thereto, peripherally of said 60 shaft, but is incapable of movement longitudi- nally of said shaft, means for applying a pre- determined load to said specimen of material to be tested while effecting rotation thereof, in- cluding a disc member through which said shaft 65 projects, such disc being capable of relative movement with respect to said shaft, said disc carrying a scale over which said pointer is adapt- ed to travel during the relative movements of said shaft and disc, means for mounting on said 70 shaft a specimen to be tested, a second pointer carried by said disc and an adjustable co-oper- ating scale extending marginally of said disc but mounted independently thereof.

5. In an apparatus for measuring the bending characteristics of material, the combination com- 75

prising a support for a specimen of material to be tested, a load-carrying and force-developing member rotatable about said support, removable and adjustable weights on this member, adjustable attachments also mounted on this member for transmitting the desired static or dynamic load or force reaction to a specimen of material mounted in said support and a pointer carried by said support and adapted to rotate therewith

but being capable of adjustment relative thereto, a co-operating scale carried by said load-applying member, a second pointer carried by said load-carrying and force-applying member and a co-operating adjustable scale mounted in proximity to but separate from said load-applying member.
